US00D909387S

(12) **United States Design Patent** (10) Patent No.: **US D909,387 S**
Turksu et al. (45) Date of Patent: ** Feb. 2, 2021

(54) **HUB FOR SMART PHONE**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA, LLC**, San Diego, CA (US)

(**) Term: **15 Years**

(21) Appl. No.: **29/699,803**

(22) Filed: **Jul. 29, 2019**

Related U.S. Application Data

(63) Continuation of application No. 29/668,265, filed on Oct. 29, 2018.

(57) **CLAIM**

What is claimed is the ornamental design for a hub for smart phone, as shown and described.

DESCRIPTION

FIG. 1 is a top, front, right perspective view of a hub for smart phone showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof; wherein the broken lines are for illustrative purposes only and form no part of the claimed design.

1 Claim, 3 Drawing Sheets
